UNITED STATES PATENT OFFICE.

BURTON F. BLACKALL AND JOHN C. DECKER, OF ROCHESTER, NEW YORK.

POLE FOR GALVANIC BATTERIES.

SPECIFICATION forming part of Letters Patent No. 274,899, dated April 3, 1883.

Application filed January 27, 1883. (No model.)

To all whom it may concern:

Be it known that we, BURTON F. BLACKALL and JOHN C. DECKER, of Rochester, in the county of Monroe, in the State of New York, have invented new and useful Improvements 5 in Poles for Galvanic Batteries, of which the following, taken in connection with the accompanying drawings, is a full, clear, and exact description.

10 This invention consists in an improved construction of a battery-pole or carbon battery-cup which is simpler and less expensive than other batteries of that class, and at the same time presents a greater amount of carbon surface in a most effective manner.

15 The invention also consists in the combination, with the aforesaid improved carbon-cup, of a cap composed of brass or phosphor-bronze and detachably connected to an extension of 20 one of the sides of said cup, and a binding-post affixed to said cap. This arrangement of the removable cap admits of readily cleaning, repairing, or renewing the same when required, all as hereinafter more fully explained, 25 and set forth in the claim.

20 The invention is fully illustrated in the annexed drawings, wherein Figure 1 is a perspective view of our improved carbon battery-cup, and Fig. 2 is a vertical transverse section 30 of the same.

Similar letters of reference indicate corresponding parts.

35 *a a* and *a'* represent the walls of the battery-cup, joined preferably at right angles at their longitudinal edges. These walls are formed of carbon plates, which are fastened together either by rubber bands *d d* sprung around them or by any other suitable means. In the carbon frame or case thus formed we 40 pack broken carbon, and retain it therein by

seals *b b* of asphaltum or other suitable cover applied to the ends of said frame or case. One of the carbon walls or plates, *a'*, is formed with a vertical extension, and to the end of this we detachably connect a cap, *A*, of brass 45 or of phosphor-bronze, provided with a binding-post, *e*, for the attachment of the conducting-wire *f*. In order to guard against corrosion of the said cap by its exposure to the chemicals in which the carbon pole is set, we 50 cover the joint around the cap with rubber cement, or other suitable non-conducting coating.

We do not claim, broadly, the combination of the packing of broken carbon with any suitable inclosing-case, as we are aware that the same is not new; but

What we do claim as our invention, and desire to secure by Letters Patent, is—

The improved battery-pole consisting of the 60 solid carbon plates *a a a* and *a'*, joined at right angles at their longitudinal edges, the broken carbon *C*, confined between said plates by the seals *b b*, means, *d*, for clamping the carbon plates around the broken carbon, and the cap 65 *A*, composed of brass or other conducting metal and detachably secured to an extension of the plate *a'*, and the binding-post *e* on said cap, all constructed and combined substantially in the manner described and shown.

In testimony whereof we have hereunto signed our names and affixed our seals, in the presence of two attesting witnesses, at Rochester, in the county of Monroe, in the State of New York, this 22d day of January, 1883.

BURTON F. BLACKALL. [L. S.]
